UNITED STATES PATENT OFFICE.

FREDERIC A. DELANO, OF CHICAGO, ILLINOIS.

RAILWAY-CAR.

1,174,057.

Specification of Letters Patent.

Patented Mar. 7, 1916.

Application filed November 24, 1913. Serial No. 802,794.

To all whom it may concern:

Be it known that I, FREDERIC A. DELANO, a citizen of the United States, residing at Chicago, in the county of Cook and State of Illinois, have invented certain new and useful Improvements in Railway-Cars, of which the following is a specification.

This invention relates to improvements in railway passenger cars, and has for its chief object a provision of means to prevent "telescoping" of cars in event of collision.

In long passenger equipment cars, such as are used in America, the floor system, whether built of wooden beams heavily trussed, or wooden beams reinforced with steel, or of steel beams, is by far the heaviest and strongest part of the car, and in event of a collision it frequently happens that one end of a car becomes tilted so that it slides either under or over the next car to it, thus causing two cars to telescope, resulting in great loss of life. There is no way of strengthening the side frame of the car enough to prevent this, because, of necessity, the floor system will always be far stronger and heavier than the side frame. To eliminate this action I provide means on each car adapted to engage with the adjacent car at either end to prevent relative rising beyond a slight amount of either car with respect to the other, thereby insuring the reception of the shock and stress of the collision by the comparatively strong car underframe. This and other objects are set forth in the following specification and shown in the accompanying drawing, in which—

Figure 1 is a perspective end view of a common form of end vestibule passenger car; Fig. 2 is a longitudinal detail section showing my device applied to a car; and Fig. 3 is a detail plan showing the interlocking relation of adjacent ends of two cars with my invention applied thereto.

Like numerals refer to like elements throughout the drawings, in which—

10 designates generally a modern type of car having the vestibule 11 and buffer plates 12. Stems 13 extend rearwardly from these buffer plates and coact with yieldable spring members 14 to resist the end shock or stress to which the car is ordinarily subjected. This is a well known and conventional form of construction, and does not form any part 55 of my invention.

I preferably construct the buffer face

plates with a plate portion 15 extending downwardly therefrom and coextensive with somewhat less than half the length of said buffer face plate and located on the right 60 hand side of the same in the form shown. This plate portion terminates in the angularly disposed outwardly extending flange 15^a for a purpose to be hereinafter described. The adjacent end of the car 65 coupled to the one shown is provided with a similar buffer face plate, the two plate members 15 and flanges 15^a being relatively located, as shown in Fig. 3, so as to fit opposite each other when the buffer face 70 plates are in contact.

It will be apparent that in the construction shown when the cars are forced together, should the force to which they are subjected be the result of a collision or the 75 like, so long as one car floor is prevented from tilting up or down, over or under the adjacent car the entire shock and stress will be borne by the underframe construction of the cars. I allow for this by making 80 these flanges 15 less than half the width of the buffer face-plate in this construction and my device will also permit a certain amount of relative up and down movement as well as lateral movement, as will be ob- 85

vious from an examination of the drawing. It will be apparent that while I have shown my invention as applied to a buffer face plate, the appliance of the same will be varied according to the car structure with 90 which it is used; and I do not wish to be restricted to the form shown and described beyond the scope of the appended claims.

What I claim is:—

1. In a car, a buffer plate having the 95 lower portion of one side thereof cut away, and a forward projection on the lower portion of the opposite side thereof, said forward projection being arranged to project beneath the buffer plate of an adjacent car 100 and prevent the rising and riding of one car over another.
2. In a car, a buffer plate, a downwardly extending plate formed integrally with the 105 said buffer plate along a portion of the lower edge thereof, said downwardly extending plate having its lower edge outwardly turned to form a flange, said downwardly extending plate being oppositely disposed with reference to the correspond- 110 ing plate of an adjacent car whereby the projecting flange of each downwardly ex-

tending plate is adapted to coact with the lower edge of the buffer plate carried by the adjacent car at the end thereof opposite the downwardly extending plate formed on the last mentioned buffer plate.

3. In a car, a buffer plate having the lower portion thereof recessed along substantially one-half its length, and an outwardly projecting portion formed on the lower edge of the remaining portion of its length, said outwardly projecting portion

being adapted to enter the recess formed in the buffer plate of an adjacent car and to engage said last-named buffer plate to prevent the rising and riding of one car over another.

In testimony whereof, I have subscribed my name.

FREDERIC A. DELANO.
